PRODUCTION OF MOTOR FUEL OF LOW SULPHUR CONTENT

Filed Oct. 31, 1940

UNITED STATES PATENT OFFICE

2,319,354

PRODUCTION OF MOTOR FUEL OF LOW
SULPHUR CONTENTCurren C. Sperling, Elizabeth, N. J., assignor to
Petroleum Conversion Corporation, Elizabeth,
N. J., a corporation of Delaware

Application October 31, 1940, Serial No. 363,595

7 Claims. (Cl. 196—24)

My invention relates to vapor phase cracking systems in which a hydrocarbon heat-carrier gas is commingled with a stream of sulphur-bearing hydrocarbon vapors to produce cracking thereof, and has for an object the provision of a reliable and effective method and means for obtaining a substantially sulphur-free motor fuel therefrom.

Due to the corrosive action in an internal combustion engine of any sulphur compounds which may be contained in motor fuel, the permissible sulphur content, by present day standards, should not exceed about 0.2% by weight. Since many petroleum stocks are characterized by a relatively high sulphur content, from 0.5 to 5.0% by weight, the problem of removing the sulphur is very important, and one to which considerable time and research has been devoted. The sulphur removal problem is complicated by the fact the sulphur compounds may be exceedingly complex and because of their chemical and physical characteristics; for example, they may fall within the boiling range of the motor fuel; they may not readily react with sulphur-removing agents or reagents which are inexpensive, and they may require reagents which themselves produce material degradation of the motor fuel, or end products.

It is a further object of my invention to provide a combination cracking and sulphur-removing system characterized by the conversion of the complex sulphur compounds into readily removable sulphides, which are then removed without degradation of the end product.

In carrying out my invention in one form thereof, a stream of heated hydrocarbon vapors is commingled with a high temperature stream of heat-carrier gas and the mixture retained in a reaction chamber for the cracking of the vapors. The temperature within the reaction chamber ranges from about 975° to 1075° F. To control the conversion of the sulphur compounds, a substantially sulphur-free heat-carrier gas is supplied; and in quantity such that the gas to oil vapor ratio is maintained high, as of the order of 1 to 3 by weight. The complex sulphur compounds then break down into removable sulphides, such as hydrogen sulphide, to the substantial exclusion of sulphur compounds in the gasoline range. For the removal of all of the sulphides, all of the vaporizable reaction products are intimately contacted with a sulphide removing agent. Preferably the sulphur-free heat-carrier gas is derived from the cracking system itself.

For a more complete understanding of my invention reference should now be had to the drawing, in which I have diagrammatically illustrated

a system embodying a preferred form of my invention, the single lines symbolically representing the connecting pipe lines.

Referring to the drawing, I have shown my invention in one form as applied to a vapor phase cracking process in which a charging stock, such for example as a sulphur bearing gas oil, is supplied by way of line 10 to a pump 11 which forces it by way of lines 12 and 13 through the heating coil 14 of a double end-fired heater 15. From transfer line 16 the oil, under the control of a pressure regulating valve 17, is discharged into a flash drum 18. To assist in vaporizing the heated gas oil, a heated flash gas from a supply line 20 is through line 21 introduced into the lower part of the flash drum. The flash gas, substantially free of all sulphur compounds preferably comprises hydrocarbon compounds chiefly consisting of those having less than three carbon atoms per molecule. Additional flash gas is introduced into the upper part of the flash drum through line 22, the latter gas serving to dry the vapors withdrawn through the overhead outlet line 23. The valves 21a and 22a are preferably included to control the quantity of flash gas entering the flash drum. The derived stream of vapors along with the flash gas passes through line 23 to a heating coil 24 of the heater 15 and under the control of valve 25 this heated stream of vapors enters the transfer line 26 at the mix point 27. Preferably the vapors are heated to within or just below the range of their cracking temperature (to about 900° F.) and during a time interval insufficient for material cracking to occur.

Concurrently with the foregoing operation, a heat carrier or cycle gas is derived from the gas made in the cracking system, and as shown, a gas consisting chiefly of hydrocarbon compounds having between 3 to 5 carbon atoms per molecule flows through line 30, is elevated in temperature by heat exchanger 31, and through line 32 enters the heating coil 33 of a double end fired heater 34. At a temperature of 1200° F. or above the cycle gas flows by way of line 35 and under the control of valve 36 enters the transfer line 26 at the mix point 27. The roof and floor tubes in both the right and left hand fire chambers of the heater 34 are utilized in the heating of the cycle gas to its relatively high temperature.

As will be explained more in detail hereinafter, the cycle gas or heat-carrier gas is maintained substantially free of all sulphur compounds. In quantity it preferably bears a ratio of about 1 to 3 by weight to the vapors entering the transfer line 26.

I have found that under the operating conditions specified the sulphur compounds in the vapors tend to, and do, form hydrogen sulphide and other removable sulphides, to the substantial exclusion of those sulphur compounds which fall within the gasoline range. Thus in accord with my invention, the chemical reaction is so controlled as to induce the formation of removable sulphur compounds which do not fall within the gasoline range, and/or which are readily removable without degradation of the final product of gasoline.

From my own investigation and research, I have found that as the sulphur content rises in the cycle and flash gases, more and more sulphur compounds are formed which fall within the gasoline range, which compounds cannot be easily and inexpensively removed from the gasoline. However, by maintaining a substantially sulphur-free heat-carrier or cycle and flash gas and by maintaining a relatively high ratio of gas to the oil vapors, the sulphur compounds are converted to the removable sulphides. The particular manner of removing the sulphides will be set forth in detail hereinafter.

The heat-carrier cracking system thus far described is characterized by a gasoline yield comparable to and exceeding that of liquid phase cracking systems, and in particular is characterized by an end product having exceedingly high anti-knock characteristics. For example, the typical range of the octane numbers of gasoline is between 78 and 95, 1939 research method. Further in accord with my invention, there is no degradation of end products either as to octane number or to yield as the result of the sulphur removal, in contrast with the material degradation resulting from conventional systems of removing sulphur from the end product of gasoline.

Again referring to the drawing, the mixture of heat-carrier gas and heated vapors is retained in a reaction chamber 38 for a suitable period of time (one of three minutes) and then discharged to a scrubber 39, preferably provided with a number of bubble caps and trays (not shown) near the top thereof. The reaction products are scrubbed by a relatively large volume of scrubbing medium comprising the residual oil from the flash drum 18 which through line 41 mixes with the residuum from the bottom of the scrubber 39. The residuum is preferably cooled at 42 and by pump 43 forced into the transfer line between the reaction chamber and scrubber for intimate mixture with the reaction products. Residuum may be withdrawn from the system under the control of valve 44.

A vaporous overhead stream is taken from the scrubber 39 by way of line 45, the heat exchanger 31 included in the cycle gas line 30, and discharged by line 46 into the lower portion of a bubble tower or fractionator 47. A relatively heavy fraction, such as gas oil, may be taken from the lower part of the bubble tower and by pump 48 introduced into the upper part of the scrubber 39 as reflux therefor. The bottoms from the bubble tower, forming the recycle stock, pass by way of line 61, valve 62, and pump 63, and in line 13 join with the charge. The overhead stream of vapors from the bubble tower 47 is reduced in temperature by heat exchanger, a cooler, or by a condenser as indicated at 65.

In accordance with my invention, it is at this point that I prefer to introduce the sulphur removing agent, and for this purpose I provide a

5 supply tank 66. The agent, by pump 67, may be introduced, under the control of valve 69, into the line 68 ahead of the cooler or main condenser 65; or, under the control of valve 70, it 10 may be introduced into the line 68 after the cracked products have passed through the cooler 65. In either case the sulphur removing agent is introduced into an elongated zone, the transfer line, in which it intimately mixes with the cracked products. The mixture then 15 preferably passes into a contact tower 71 which may consist of an accumulator provided with a plurality of baffles, or it may be filled with any suitable mechanism such as rock wool to insure further intimate contact between the sulphur removing agent and all of the material removed through line 68 from the bubble tower.

The sulphur removing agent may be selected from any one of the numerous materials known 20 by those skilled in the art to be reasonably effective in chemically uniting with the sulphides to produce products or precipitates which are heavier than the products suitable for inclusion in motor fuel. I have found that a water wash 25 including 10% by weight of sodium hydroxide (NaOH) is quite satisfactory. This 10% solution of sodium hydroxide may be obtained from partially spent sodium hydroxide, first utilized for other purposes in the refinery, and by partial 30 recovery systems the same reagent may be used over and over again, thus reducing to a negligible amount the cost of removing the sulphur from the system. As I have indicated, any suitable agent may be utilized and by way of further 35 example the following agents will be satisfactory:

(1) Tri-potassium phosphate from which hydrogen sulphide may be regenerated by heating the extracted medium;

(2) A concentrated aqueous solution of sodium 40 phenolate or sodium salts of tar acids as extraction media from which the hydrogen sulphide can be regenerated and the media recycled. Other methods are known to the art and those most desirable are the regenerative and recycling operations which produce as a by-product, the hydrogen sulphide which may be used for the production of sulphuric acid.

Although I prefer to use an active agent, under some circumstances it may be practical to use water, into which the hydrogen sulphide may be dissolved, as suggested by Sachs Patent 45 #1,872,349, dated August 16, 1932.

Regardless of which sulphur-removing agent is used it must be supplied in sufficient quantity to remove all of the hydrogen sulphide. For example, if a solution of sodium hydroxide were used two mols of sodium hydroxide must be used for each mol of hydrogen sulphide removed from the cracking unit.

60 The desirability of sulphur removal is set forth in said Sachs patent, but one material and essential difference therefrom is the failure of the Sachs disclosure to provide for the removal of sulphur compounds from both the condensate and the gas. In consequence, the end product of gasoline contained more than the permissible amount of sulphur for those crudes of relatively high sulphur content. Moreover, the Sachs disclosure failed to utilize rich C₃ and C₄ hydrocarbon gases for his heat-carrier, a matter of real importance to applicant's invention. I have further determined that secondary reactions of the sulphur compounds can and do take place in low temperature zones, such as in the stabilizer, so that higher boiling sulphur compounds,

those within the boiling range of gasoline, are formed and make the gasoline undesirable for motor fuel. In accordance with my invention these sulphur compounds are removed while in their removable state as sulphides and before any secondary reaction to high boiling compounds.

After the sulphur-removal treatment, the reaction products and the sulphur removing agent flow through line 12 from the contactor or treater 11 and they pass together into a low pressure accumulator 13, having adequate capacity for the settling of the water and sulphur products from the hydrocarbon condensate. The water and sulphides are withdrawn by way of line 14, under the control of valve 15, automatically operated by an interface controller 16 of any suitable type. The interface controller is an instrument well known to those skilled in the art and no further explanation is needed herein other than to say that it functions in response to change in level of the interface between the water and the condensate. If the interface tends to rise because the water and sulphur compounds are entering in a greater quantity than they are leaving the accumulator, the interface controller 16 operates the valve 15 to increase the rate of withdrawal. Conversely, if the interface tends to fall, valve 15 is closed somewhat to hold constant the level of the interface.

Condensate is withdrawn from the accumulator 13 by a pump 47a and under the control of valve 47b passes into the upper part of the bubble tower as reflux therefor. From the top of the low pressure accumulator, gas is withdrawn into a compressor 71, discharged therefrom at about 250# per square inch, reduced in temperature in cooler 79, and discharged into a high pressure accumulator 80. A second stream of condensate is withdrawn from the accumulator 13 by pump 81 and joins with the compressed gas in line 78 and passes with it into the accumulator 80. In this manner condensable constituents in the gas withdrawn from the low pressure accumulator are removed as a condensate in the high pressure accumulator 80. It is to be understood a recovery system of the absorber type may be used instead of the compression type of recovery system described and illustrated herein. Condensate from the high pressure accumulator passes by way of pump 83, under the control of valves 84 and 85, into a stabilizer 86, provided with a plurality of bubble caps and trays (not shown).

In the stabilizer, as is well understood in the art, heat is supplied to the lower part thereof as by a reboiler 87 and stabilized gasoline is withdrawn therefrom and sent to storage under control of valve 88 and by way of line 89. The reboiler oil circuit is indicated at 90 and 91. The lighter constituents withdrawn from the top of the stabilizer 86 are reduced in temperature by a cooler 92, and the resulting condensate collected in accumulator 93, from which it is returned by pump 94 to the stabilizer as reflux therefor. The constituents removed in the stabilization of the cracked gasoline comprise hydrocarbons having 3 to 4, and some 5 carbon atoms per molecule, more and less, and these rich gases pass by way of line 30 to form the chief supply of cycle or heat-carrier gas for the operations described above. In case these gases are insufficient in quantity for the supply of the required amount of cycle gas, additional gas derived from the high pressure accumulator 80, by way of line 95, may, under the control of 75

valve 96, join with the stabilizer tops which comprise the gases rich in C₃'s and C₄'s. The gas derived from the high pressure accumulator is known as the make gas and part of it under the control of valve 97 may be discharged from the system through line 98, while the remaining part thereof, under the control of valve 99, flows by way of line 100 to the convection bank 101 of the double end fired heater 34 and forms the supply of the heated flash and drying gas introduced by way of line 20 into the flash drum 18, as above described.

In a system embodying my invention I have produced substantially sulphur-free gasoline from relatively high sulphur-bearing petroleum fractions. And in those instances where the sulphur content slightly exceeded the permissible sulphur content in the end product or gasoline, I have by blending with a straight-run gasoline of low sulphur content, produced a highly satisfactory, marketable gasoline of high anti-knock value, and of satisfactorily low sulphur content, for example less than .2% by weight of sulphur. Moreover, my invention has made possible the production of marketable gasoline, sufficiently low in sulphur, from crudes having a sulphur content so high as to heretofore have been considered of no value as charging stock for cracking systems for the production of gasoline. Thus, my invention has made feasible the economic utilization of high sulphur-bearing charge oils which were hitherto considered of no value as charging stocks for the production of marketable gasoline.

By way of further illustration and not of limitation, my invention has been applied to charge oils including those set forth in the following tabulation:

	Charge at line 10	Allegan Michigan reduced crude	Freeman Michigan reduced crude	Black Mt. Wyoming gas oil
45	Gravity °API.....	23.8	31.6	27.7
	Sulphur wt. per cent.....	1.13	0.82	2.27
	Cracking temp. °F. in chamber 38.....	980	990	1000
	Cracking pressure in chamber 38.....	100	100	100
50	<i>Cracked gasoline leaving line 89</i>			
	Volume per cent of charge.....	49	70	55
	Gravity °API.....	57.0	59.0	56.0
	Octane MM.....	72	70	79
	Octane 1939 res.....	85	85	95
	Sulphur per cent by weight.....	0.09	0.07	0.32
55	<i>Hydrogen sulphide removed in line 74</i>			
	Weight per cent of charge.....	0.2	0.7	0.8
	Weight per cent of available sulphur.....	20.0	85.0	35.0

60 Taking the Black Mountain Wyoming gas oil as illustrative it will be observed the sulphur content of the gas oil is 2.27 weight per cent, an amount which has made this particular crude of little value as a charging stock for the production of cracked gasoline. In accord with my invention, this high percentage of sulphur, under the controlled conditions of temperature and pressure and sulphur-free character of the heat-carrier or cycle gas, was converted to removable sulphides to such a degree that only 0.32% by weight of sulphur appeared in the stabilized gasoline. Thus, by blending with low-sulphur gasoline a marketable, high octane gasoline was produced. Specifically by blending 33½% of straight run having a sulphur content of 0.1%

by weight, a gasoline was produced, having a sulphur content not above about .2% by weight.

More specifically with respect to the Black Mountain Wyoming gas oil, the weight of a 42 gallon barrel is about 311 pounds. There is present therein around 7.07 pounds of sulphur. In line 14 there will be removed about 2.49 pounds of hydrogen sulphide, which in terms of per cent of hydrogen sulphide removed against the total pounds of sulphur, comes to about 35%. A part of the remaining sulphur is removed with the residuum discharged under control of valve 44 so that only the 0.32% by weight of sulphur remains in the stabilized gasoline. For crudes having a sulphur content as high as 2% by weight, gasoline may be produced which, without further blending or treatment, will have a sulphur content not exceeding 0.2% by weight.

Moreover, by removing the sulphur from the cracked liquid products immediately after their exit from the bubble tower, there is no opportunity for secondary reactions of the sulphur compounds contained therein. These sulphur compounds as they exist in the overhead stream from the bubble tower largely comprise readily removable sulphides. I have discovered that if they are not immediately removed, as by admixture with a sulphide removing agent either before or after passage through the main condenser 65, these sulphides will be converted by secondary reactions into more complicated compounds such as the mercaptans, which are exceedingly difficult and uneconomical to remove from the motor fuel. I have further discovered that the time and temperature conditions existing in the usual stabilizing column such as column 86 are sufficiently favorable for the occurrence of these undesirable secondary reactions.

My invention is further characterized by the fact the sulphur is removed as a by-product of the system. Since the sulphur is in the form of sulphides (largely hydrogen sulphide) upon regeneration of the sulphur-removing agent the sulphides given off therefrom may be used for the production of sulphuric acid in manner well understood by those skilled in the art.

While I have shown a particular embodiment of my invention, it will be understood that I do not limit myself thereto since many modifications may be made, and I therefore contemplate by the appended claims to cover any such modifications as fall within the spirit and scope of my invention.

What I claim is:

1. In a vapor phase cracking system in which a gaseous hydrocarbon heat carrier is commingled with and utilized for the cracking of a stream of heated sulphur-bearing hydrocarbon vapors, the method of maintaining low the sulphur content of the end product which consists in maintaining a high ratio of said gaseous heat-carrier to said hydrocarbon vapors during the cracking thereof, fractionating and cooling the cracked products, contacting both the gaseous and liquid constituents of said cracked products with a sulphide removing agent, separating said agent and said sulphides from said gaseous and liquid cracked products, separating from said products heat carrier gas having a sulphur content sufficiently low to promote the formation of removable sulphides from said heated sulphur-bearing vapors, and separating from said liquid products a motor fuel end-product characterized by its low sulphur content and its high anti-knock value.

2. In a vapor phase cracking system in which a gaseous hydrocarbon heat carrier is commingled with and utilized for the cracking of a stream of heated sulphur-bearing hydrocarbon vapors, the method of maintaining low the sulphur content of the end product which consists in maintaining a ratio of at least unity by weight between said gaseous heat-carrier and said vapors, fractionating and cooling the cracked products, contacting both the gaseous and liquid constituents of said cracked products with a sulphide removing agent, separating said agent and said sulphides from said gaseous and liquid cracked products, separating from said products heat carrier gas having a sulphur content sufficiently low to promote the formation of removable sulphides from said heated sulphur-bearing vapors, heating said separated cycle gas to a high temperature and commingling it with said stream of sulphur-bearing vapors to promote cracking thereof and to convert the contained sulphur content into removable sulphides, and separating from said products a motor fuel end-product characterized by a sulphur content sufficiently low for non-corrosive use in internal combustion engines.
3. In a vapor phase cracking system in which a hydrocarbon heat carrier is commingled with a stream of heated sulphur-bearing hydrocarbon vapors to assist in the cracking thereof, the method of maintaining low the sulphur content of the end product which consists in maintaining a ratio above unity by weight between said gaseous heat-carrier and said vapors, fractionating and cooling the cracked products, in an elongated zone of restricted cross-sectional area intimately mixing a sulphide removing agent with the gaseous and liquid constituents of said cracked products, passing said mixture into an enlarged zone, separately withdrawing therefrom said agent and sulphides, said gaseous constituents, and said liquid hydrocarbon constituents, supplying said agent in quantity to maintain the ratio of the agent to the cracked products sufficiently high to produce substantially sulphur-free gaseous and liquid hydrocarbon constituents, and withdrawing said last-named constituents from said enlarged zone.
4. In a vapor phase cracking system in which a hydrocarbon heat carrier gas is commingled with and utilized for the cracking of a stream of heated sulphur-bearing hydrocarbon vapors, the method of converting the sulphur compounds contained in said vapors into removable sulphides which comprises, maintaining a ratio of at least unity by weight between said gaseous heat-carrier and said vapors, fractionating and cooling the cracked products produced as a result of the mixing of the vapors with the heat-carrier gas, in a conduit introducing into intimate contact with said cracked products a sulphide removing agent, in an enlarged zone subdividing said mixture to provide further intimate contact of the agent with said products, in a second enlarged zone gravity-separating said agent and said sulphides from said gaseous and liquid products, recovering from said gaseous products constituents suitable for inclusion in motor fuel, the remaining gaseous products in large part forming the supply of said hydrocarbon heat carrier gas whose sulphur content is maintained by said sulphur removal below about 0.01% by weight to cause said sulphur bearing compounds contained in said vapors during the

tracking reaction to be converted into removable sulphides.

5. In a vapor phase cracking system in which a hydrocarbon heat-carrier gas is commingled with a stream of heated sulphur-bearing hydrocarbon vapors to assist in producing cracking thereof, the method of converting the sulphur compounds contained in said vapors into removable sulphides, such as hydrogen sulphide, which comprises supplying a substantially sulphur-free heat carrier gas for mixture with said vapors to crack them, while maintaining high, on the order of 1 to 3 by weight the ratio of said gas to said vapors, cooling and fractionating the reaction products, intimately washing and scrubbing said products with a sulphide removing agent, in an enlarged zone separating said agent and the removed sulphides from said cracked products, and separating from said cracked products said substantially sulphur-free gas to form the supply of said heat-carrier gas, and withdrawing from the system a motor fuel end-product characterized by a sulphur content below about 0.2% by weight.

6. The method of producing a gasoline having a sulphur content not exceeding 0.2% by weight from a crude having a sulphur-content of about 2.0% by weight, which comprises deriving from the crude a stream of hot sulphur-bearing hydrocarbon vapors, commingling therewith a gaseous hydrocarbon heat carrier which supplies heat for the cracking of said vapors, maintaining a ratio of at least unity by weight between said gaseous heat-carrier and said vapors, fractionating and cooling the cracked products, contacting both the gaseous and liquid constituents of said cracked products with a sulphide remov-

ing agent, separating said agent and said sulphides from said gaseous and liquid products, separating from said products heat carrier gas having a sulphur content sufficiently low to permit the formation of removable sulphides from said heated sulphur bearing vapors, and separating from said liquid products a motor fuel characterized by a sulphur content not exceeding 0.2% by weight and by a high anti-knock value.

7. The method of producing from a charging stock having a high sulphur content a motor fuel having a low sulphur content, which comprises deriving a stream of heated sulphur-bearing hydrocarbon vapors from said charging stock, cracking the same by commingling therewith a high temperature gaseous hydrocarbon heat-carrier, maintaining a high ratio of said gaseous heat-carrier to said hydrocarbon vapors during the cracking thereof, fractionating and cooling the cracked products, preventing secondary reactions of the sulphur compounds in said cracked products with a sulphide removing agent, separating said agent and said sulphides from said gaseous and said liquid products, separating from said products said heat carrier gas with a sulphur content sufficiently low to induce the formation of removable sulphides during the cracking of said sulphur-bearing vapors and comprising a substantial proportion of C₃ and C₄ compounds, and in the substantial absence of secondary reactions of said sulphur compounds separating from said liquid products a motor fuel characterized by a sulphur content not exceeding 0.2% by weight.

CURREN C. SPERLING.
